HENRY HUEBER, OF SEATTLE, WASHINGTON, ASSIGNOR TO ARNOLD A. BARKEY, OF SEATTLE, WASHINGTON.

COOLING SYSTEM FOR AUTOMOBILES.

1,255,168.

Specification of Letters Patent. Patented Feb. 5, 1918.

Application filed February 12, 1917. Serial No. 147,992.

To all whom it may concern:

Be it known that I, HENRY HUEBER, a citizen of the United States, residing at Seattle, in the county of King and State of Washington, have invented certain new and useful Improvements in Cooling Systems for Automobiles, of which the following is a specification.

This invention relates to improvements in cooling systems for automobiles and has for its object the provision of means for increasing the rapidity of circulation of the water by the motor water jacket through maintaining a partial vacuum within said radiator or the discharge point of the heated water from the said water jacket, and the introduction of air within the water circulating system at the intake point of the circulating water within said water jacket. With these and other objects in view, the invention consists in the novel construction, adaptation and combination of parts of a water circulating system, as will be fully described in the following specification, illustrated in the accompanying drawings, and pointed out in the appended claim.

In said drawings, Figure 1 is a view partly in side elevation and partly in vertical section of apparatus embodying my invention as applied to an automobile.

Fig. 2 is a similar view to Fig. 1, viewing the same from the diametrically opposite side of the automobile.

Figs. 3 and 4 are longitudinal sectional views of details of the invention.

Referring to said views, the reference numeral 1 indicates the body frame of an automobile and 2 a radiator of suitable form for cooling the water employed in the water jacket of the motor 3. 5 indicates the upper water circulating pipe connecting said water jacket with the radiator, and 6 the lower water circulating pipe connecting the lower portion of said radiator with the inlet 5 to said jacket. 7 indicates the filling neck whereby water is introduced into the radiator, and 8 a threaded cap or closure therefor. Said cap is provided with a relief valve of any suitable form illustrated as consisting in a ball 10 confined within a chamber 11 and admitting of air or vapor passing outwardly through the holes 12 and 13, but not admitting air within the radiator. 15 indicates a pipe communicatively connected at one end with the interior of the

radiator above the water line thereof and illustrated herewith as extending into said neck 7. A funnel-shaped guard 14 is positioned in the neck 7 to prevent water, when introduced within the radiator, entering said pipe 15. The other end of said pipe 15 terminates in a nozzle 16 extended within the bore of the pipe 17 connecting the carbureter 18 with the gas intake manifold 20 of the motor, said nozzle 16 being positioned in the path of the gases passing through the pipe 17 and pointing in the general direction in which said gases are moving.

21 indicates a valve of any approved type adapted to control the passage of air or vapor through said connections 15, which valve is in the manual control of the driver by means of a rod 22 which extends to the dash board 23 and is incased in a flexible casing 25.

The pipe connections 6 are illustrated as entering the water jacket of the motor through a header 26 into which one extremity 28 of a tube 27 protrudes and is secured as at 30. Said extremity 28 extends into the stream of water issuing from the pipes 6 into said water jacket, and is directed in the general direction of said stream.

A bell member 31 is reduced at one end and rigidly connected to said extremity 28 and at its opposite open end of considerably larger diameter than the bore of said extremity 28, projects forwardly of said extremity into the stream of fluid.

Apertures 32 are formed in the circular wall of said bell admitting a considerable portion of said stream of water to pass through the bell and past the outlet of said extremity 28. The end of said tube 27 opposite to the extremity 28 is open to the atmosphere for the admission of air, with the exception that it is provided with a valve, indicated generally by the numeral 33, which will prevent the passage of fluids therethrough in a reverse direction. Said valve 33 is desirably positioned above the water lever of the radiator.

A movable valve member 35 is held in yielding engagement with the valve seat through a light spring 36, the tension of said spring being barely sufficient to overcome the gravity of said valve member.

The operation of my invention may be described as follows:

The current of gas passing through the

pipe 17 will create considerable suction in the nozzle 16 which is communicated through the pipe 15 as manually controlled by the valve 21, to the space above the water line in the radiator 2. The partial vacuum thus created will be effective to promote the flow of water throughout the circulatory system.

The stream of water flowing past the extremity 28 of the air inlet pipe 27 also produces an effect of suction within said pipe 27 drawing air through the valve 33 and introducing the same into said stream of circulating water. Combined with said latter suction effect, the increased velocity of the upflow of water through the pipe 6 due to the aforesaid partial vacuum in the radiator and said vacuum, results in the introduction of relatively considerable amounts of air into said stream of circulating water. Such air serves as a highly efficient cooling medium for the circulating water and furthermore serves in its escape through the water jacket into the radiator to further stimulate the circulation of the water system.

If at times the pressure of air within the radiator above the water line exceeds the atmospheric pressure, such excess will be relieved through the operation of the valve 10.

It is believed that the advantages residing in my improved apparatus will be clearly evident from the foregoing and particularly its simplicity and adaptability to practically all types of modern automobiles. The circulation of the cooling water through the motor water jacket has been demonstrated to be highly efficient and to necessitate the throttling of the suction generated through the pipe 15 by the partial

closing of the valve 21, as otherwise the water may be maintained at too low a temperature for efficient economical working of the motor.

Among the other advantages afforded by my invention is the introduction of aqueous vapor generated in the upper portion of the radiator through the pipe 15 into the manifold pipe 17, whence said vapor is introduced with the explosive gases into the engine cylinders, thereby assisting in the complete combustion of said gases and reducing the deposit of carbon.

While I have described my invention with some detail, I do not wish to be understood as confining myself to the embodiment herein shown, but wish to be limited only within the scope of the appended claim.

What I claim, is—

In a cooling system for automobiles, a motor, a water jacket therefor, a radiator, inflow and outflow pipes connecting the water jacket with the lower and upper portions of said radiator, respectively, a gas intake pipe connected with the cylinders of said motor, a tube extending from the upper portion of said radiator into said intake pipe, said tube terminating within the latter in a nozzle disposed in the direction of the current of gas flowing through said intake pipe to produce suction in said tube and a partial vacuum in said radiator adjacent said outflow pipe, an air inlet pipe extending into the stream of water entering said water jacket to produce a suction in said inlet pipe, and a relief valve in said radiator.

Signed at Seattle, Washington, this 2nd day of February, 1917,

HENRY HUEBER.
